UNITED STATES PATENT OFFICE

123,763

DESIGN FOR A COMBINED ELECTRIC LAMP CASING AND SUPPORT

Jerome J. Rieland, Los Angeles, Calif.

Application April 25, 1940, Serial No. 91,956

Term of patent 3½ years

To all whom it may concern:

Be it known that I, Jerome J. Rieland, a citizen of the United States, residing at Los Angeles, in the county of Los Angeles and State of California, have invented a new, original, and ornamental Design for a Combined Electric Lamp Casing and Support, of which the following is a specification, reference being had to the accompanying drawing, forming part thereof, in which:

Figure 1 is a side view in elevation of a combined electric lamp casing and support, showing my new design;

Figure 2 is an elevational rear view thereof; Figure 3 is a top plan view of the same; and Figure 4 is a front view in elevation.

I claim:

The ornamental design for a combined electric lamp casing and support, as shown.

JEROME J. RIELAND.
